UNITED STATES PATENT OFFICE.

HYMAN HORWITZ, OF BROOKLYN, NEW YORK.

COLLAR BUTTON.

Application filed May 19, 1926. Serial No. 110,206.

This invention relates to collar buttons and comprehends a collar button of improved formation which is especially designed for permanent attachment to one end 5 of the neckband of a shirt for engagement through a buttonhole in the opposite end and thence through the alined buttonholes of the overlapping ends of a collar.

One of the principal objects of the present invention is to provide an improved form of collar button which is so constructed as to effectually perform its function and which, at the same time, eliminates the necessity of using detachable collar buttons 15 and the objections and disadvantages incident thereto, such as the loss or misplacement of the same when needed and the necessity of changing detachable collar buttons from one shirt to another.

More specifically, the invention comprehends a permanently attached collar button which includes a substantially frusto-conical shaped shank of increasing diameters from 20 its inner connected end to its outer free end and formed on its upper portion with a notch which defines at the outer end an upwardly projecting retaining lip.

The invention furthermore aims to provide a collar button which is extremely simple, inexpensive and efficient.

With the above recited and other objects in view, reference is had to the following specification and accompanying drawings in which there is exhibited certain examples 35 or embodiments of the invention which are in no way intended as limitations upon the scope of the appended claims as it is to be clearly understood that variations and modifications which properly fall within the 40 scope of said claims may be resorted to when found expedient.

In the drawings—

Figure 1 is a perspective view of a collar button constructed in accordance with the 45 invention attached to the neckband of a shirt;

Fig. 2 is a sectional view on an enlarged scale illustrating the same in buttoned relation on the neckband;

Fig. 3 is a perspective view of the button 50 prior to its attachment to the shirt;

Fig. 4 is a perspective view of a slightly modified adaptation of the invention.

Referring to the drawings by characters 55 of reference, the improved collar button includes a substantially frusto-conical shank

10 formed in the preferred embodiment at its reduced end with a base 11 apertured at 12 to receive the stitching 13 for attaching the same to one end of the neckband A of 60 a shirt B, the opposite end of the neckband having the usual buttonhole C. The shank on its upper side is cut away or notched at 14 between the base and the outer enlarged free end to define an upstanding retaining 65 lip 15, which when the free ends or overlapping flaps are engaged thereover prevents accidental displacement from the shank in that the lip together with the flared or conical formation of the shank necessitates a 70 spreading of the buttonholes to dislodge the same.

In buttoning or engaging the buttonhole C in the neckband, or the buttonholes of the collar flaps or ends with the button 75 shank, the upper edges of the buttonholes are initially passed over the upstanding lip 15 into the notches 14 and then the lower edges of the buttonholes are engaged over the remaining portion of the enlarged outer 80 end of the shank, necessitating a stretching of the buttonholes, which due to their tendency to return to a normal position tightly grip the shank toward the minor diameters thereof. This eliminates any possibility of accidental displacement after 85 engagement.

In the modified adaptation of the invention, the button includes a frusto-conical shank 16, formed with a substantially crescent-shaped upstanding lip 17 at its outer end and provided with axially extending openings 18 through which the threads or stitching is designed to pass in effecting the attachment of the same to a shirt neckband, 95 it being, of course, understood that the reduced inner end of the shank is drawn into a flat engagement with the neckband. In use the embodiment illustrated in Fig. 4 operates precisely as that described for the 100 first form of the invention.

What is claimed is:

1. As a new article of manufacture, a collar button including a substantially frusto-conical shank presenting axially increasing 105 diameters from its inner to its outer end and provided with a radially projecting retaining lip at one side of its outer enlarged end.

2. As a new article of manufacture, a collar button adapted for permanent attachment to one end of the neckband of a shirt, 110

said button including a shank of gradually increasing diameters axially toward its outer enlarged end, and a radially projecting retaining lip at one side of its enlarged outer 5 end.

3. A collar button adapted for permanent attachment to one end of the neckband of a shirt, including a shank insertable through a buttonhole at the opposite end of the neck 10 band and through the buttonholes of the overlapping ends of a collar, said button shank being of gradually increasing diameters from its inner attached end to its outer free end, and a radially projecting lip at one side of its outer end co-operating 15 with the inwardly converging portions of the surface to prevent accidental displace-

ment of the collar and neckband therefrom.

4. A collar button, including a shank of substantially frusto-conical formation, an 20 apertured base at the reduced end for attaching the same, and a notched portion between the base and the outer end defining a retaining lip projecting radially from one side of the outer end. 25

5. A collar button, comprising a substantially frusto-conical body having apertures extending axially therethrough for attaching the same by stitching, and a crescent shaped radially projecting integral retaining 30 lip at one side of the enlarged end of the body.

HYMAN HORWITZ.
